NOISE REDUCTION SYSTEM

R. Lee Hollingsworth, Riverhead, N. Y., assignor
to Radio Corporation of America, a corporation
of Delaware

Application April 17, 1942, Serial No. 439,363

7 Claims. (Cl. 250—20)

My present invention relates to a circuit for the reduction of man-made noise and static, as well as atmospheric static of certain kinds such as sharp clips and short clashes.

Man-made static such as ignition, commutator ripple, etc., are often several times as strong as the desired signal, whether it be the carrier or modulation level which one wishes to listen to, or use. These short, high-amplitude impulses represent a considerable amount of energy, and are capable of actuating a reproducing unit to such an extent as to make listening undesirable. Likewise in radio-telegraph reception, when these strong impulses are passed directly into a narrow band filter, they set up a ringing in the circuit beyond the filter, as a result of overloading the filter, which lengthens the duration of these clicks and short static crashes. If these impulses are instantaneously reduced, or eliminated entirely, they become tolerable through a reproducing unit (loud speaker); or are discriminated against by the aforesaid narrow band filter in radio telegraphy because of non-overloading.

An important object of my invention is to provide a method of controlling high amplitude noise and static components of short duration; the method including the steps of rectifying received signal energy, grid-controlling the rectification from an auxiliary rectifier which becomes operable to high level components, and reduces, or cuts off completely, the output of the signal rectification instantaneously during reception of high level noise impulses.

Another object of the invention is to provide a noise impulse rectifier for controlling the signal demodulator of a receiver; an auxiliary rectifier being provided to rectify solely amplified modulation signals, the output of the auxiliary rectifier functioning through a time delay circuit to control the noise rectifier sensitivity as a function of the modulation signal level.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

Fig. 1a shows a receiver embodying the invention.

Fig. 1b shows a modification.

Fig. 2a to 2d inclusive illustrate the functioning of the noise control system.

Referring now to Fig. 1a, the modulated carrier wave collector 1 is coupled to radio frequency amplifier 2. The collector 1 may be a grounded antenna system, as well as the dipole shown. The amplifier may comprise one or more tunable amplifiers; the tuning range may be in any of the well known bands. The amplified energy, which 5 may comprise modulated carrier wave energy having noise and static impulses superposed thereon, is passed to a mixer 3. The latter may be of the combined first detector-local oscillator type, or the first detector may be independent of the oscillator. Since superheterodyne practice is universally followed, that type of reception is shown. Of course, any other type of reception 10 may be used. The intermediate frequency (I. F.) output of the mixer is transmitted through the 15 I. F. amplifier 3'. The output circuit 3'' of the amplifier is resonated to the operating I. F. value, and feeds each of resonant circuits 4' and 5' as shown.

Each of circuits 4' and 5' is tuned to the operating I. F. value; they serve as input circuits for 20 respective rectifier tubes 4 and 5. Tube 4 is a grid-controlled diode so far as the applied signal currents are concerned. Physically the tube 4 is a triode whose anode is connected to the high 25 potential side of circuit 4'. The low potential side of the latter is connected to ground through load resistor 6. Modulation signal voltage, whether voice or music, is transmitted through 30 condenser 15 to transformer 16. The latter may 35 feed any desired type of audio frequency output circuit.

Direct current voltage is taken off from resistor 6, and is applied to the control grid 7' of tube 7. The plate of the latter is connected to 40 the positive terminal of direct current source 8 in series to ground with resistor 9. Cathode 8' is 45 at ground potential, and, therefore, the tube 7 is normally conductive in the absence of received signal energy and consequent absence of negative bias across resistor 6. Hence, in the absence of 50 received signal energy the voltage across resistor 9 is a maximum. The latter voltage, negative to ground, is taken off by tap 9', and is applied to the signal grids of the controlled tubes over a path comprising resistor 10, connection 11' and the various filter resistors 11''. The various tubes 55 of the amplifier 2, mixer 3 and I. F. amplifier 3' may be gain-controlled. Hence, during interstation tuning, or when the received carrier strength is too low or during selective fading

periods, the bias derived from resistor 9 reduces the gain of the receiver sufficiently to prevent reproduction of undesired noises.

When carrier-derived voltage is developed across resistor 6, the grid 7' is biased to cut-off thereby reducing the voltage across resistor 9 to zero. The AVC bias developed across resistor 6 is now fed through resistor 14, which latter resistor is in series with resistor 10, to lead 11'. Condenser 18 is connected from the junction of resistors 11 and 10 to ground. Network 11-10-18 provides proper time delay action for satisfactory operation of the AVC circuit. Rectifier diode 5 acts to draw current when the noise peaks, or signal peaks, reach above a predetermined amplitude level. The anode of rectifier 5 is coupled to the high potential side of input circuit 5'.

The low potential side is connected to ground through a path comprising resistor 12 in series with negative biasing source 13.

The voltage developed across resistor 12 is applied directly by lead 14 to the control grid of demodulator tube 4. Hence, when the impulses applied to circuit 5' override the negative bias due to source 13, there is developed a negative voltage across resistor 12 which is applied to the grid of rectifier 4 to reduce the output thereof instantaneously, or to block it entirely for the duration of the noise click or apparent over-modulated components that reach a very high level during certain types of fading. Naturally, if the desired modulation drew current through diode 5 the quality would suffer due to the demodulating effect that would take place in tube 4. Diode 5 could be made to operate, for example at 35 to 60 decibels, above rectifier 4 by reducing the coupling between circuits 3'' and 5' sufficiently to separate the current starting points between diodes 4 and 5.

The latter coupling, however, may have the same coefficient as that between 3'' and 4', but is rendered conductive to higher signal and noise levels only by inserting source 13 in series with the plate circuit of tube 5 and/or the grid circuit of tube 4. If additional control is desired, switch 19 may be inserted in the lead from the anode end of resistor 12 to the gain control connection 11'. In this way the effect of the bias from resistor 12 applied to the grid of tube 4 may be augmented by the effect of the bias applied over the closed switch 19.

Explaining the action of this circuit further, in Fig. 2a the curve A shows the amplitude of a rectified carrier, modulated 100% for a time by a tone impulse. A heavy noise click is shown extending much higher in amplitude and containing many components jammed together to give it the appearance of a square wave character. This peaked signal starts to reduce itself automatically as it exceeds the tone modulation level; this is due to the action of diode 5 on the grid of rectifier 4. In Fig. 2b, the curve B shows the noise click reduced to the approximate level of the modulation. By increasing the voltage control of rectifier 5, or by applying the control voltage to more tubes in the receiver, the demodulator 4 may be instantaneously cut off for the duration of the noise click as shown at C in Fig. 2c.

Let us assume for explanatory purposes that this tone was then passed through a narrow band filter capable of responding only to impulses not faster or shorter in duration than the impulse containing the five cycles of the tone. The tone

would start to flow through the filter, and, once started, could not change suddenly enough to drop out. Perhaps, it would dip slightly, and in most cases, if the click was short enough in duration, would not be noticeable past the filter as shown at D in Fig. 2d. If the modulation consisted of voice or music, if the click were lowered to the level of the modulation or taken out completely, it would be somewhat less objectionable.

Now let it be assumed that it was desired to listen to a program on short waves, and reception was interfered with by man-made static such as motor starters and commutation, auto ignition from the street or nearby locations. If the noise suppressing circuit operated only above the highest modulation level, then when the modulation was low, or no modulation was used at all, we would have the noise of a high order prevailing if it were not high enough to knock itself down, or out, completely. This condition can be corrected by causing the sensitivity of the noise rectifier to vary as a function of the modulation level.

Referring to Fig. 1b, let it be assumed that the tube 5'' is a triode which for signal currents acts as a grid-controlled diode. The grid of tube 5'' is connected through a time delay circuit to a rectifier that rectifies a portion of the modulation, after it has been amplified. Then, as the music decreases in volume the reduced rectified modulation voltage would allow the sensitivity of tube 5'' to be increased, and the noise that was normally above this low modulation level would be lowered in amplitude. Likewise, if the modulation stopped completely the sensitivity of rectifier 5'' would be increased to take out most all objectionable noises. In the event of a sudden increase in music level the first few impulses would be lowered, but not for longer than it would take the increased modulation level again to reduce the sensitivity of tube 5'' through the time delay circuit. There may be strong opposition to a sudden rise in modulation level, but by choosing the proper time constant values between the grid of tube 5'' and the modulation rectifier load resistance, sharp impulses of high amplitude would be reduced considerably in amplitude before reaching the modulation rectifier.

However, a series of sustained components, such as modulation, would lower the sensitivity of tube 5'', since the control factor of tube 5'' would not be sufficient to knock out each modulation component completely. Therefore, any increased level of sustained modulation (for perhaps a small fraction of a second) would start reducing the sensitivity of tube 5'' through the time delay circuit. If the control of tube 4 by tube 5'' was great enough to demodulate completely the modulation as it attempted to rise high very suddenly, then this circuit would be useless in sound broadcast reception. Therefore, the sensitivity of tube 5'' must vary slowly in sensitivity and follow the general average of the modulation level, and never have sufficient control over tube 4 to reduce completely any component within the modulation range. When the score of music is low in amplitude, as tube 4 draws current on a sudden increase in the music level, the increase must be also amplified to start decreasing the sensitivity of tube 4 quickly to a point where the modulation would not be affected by the action of tube 5'' on the grid of tube 4. The highest sensitivity to which tube 5'' might reach at any time would be perhaps from 5 to 15

decibels below the sensitivity of the current starting point of tube 4. This would insure tube 4 to be always the main signal control source, as the modulation level starts from zero, or rises from a low level passage to a higher level passage.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. A method of receiving modulated carrier wave energy which includes detecting received energy to provide modulation signals, developing a control voltage in the absence of received carrier energy, utilizing the control voltage to render inefficient the supply of electrical energy for detection, deriving a second control voltage from detected wave energy, controlling the level of wave energy subjected to detection with said second control voltage to maintain uniform said supply of energy, deriving a third control voltage from received energy whose amplitude exceeds a predetermined level, and utilizing the third control voltage to render said detection inefficient.

2. A method of receiving signaling energy which includes amplifying such energy, demodulating the energy, rectifying the amplified energy when the amplitude thereof exceeds a predetermined level thereby to provide a control voltage for preventing the reproduction of undesired noise impulses, rendering said demodulation inefficient in response to said control voltage, amplifying the demodulated energy, rectifying the amplified modulation, and controlling said first mentioned rectification action in response to the rectified modulation voltage.

3. A system for receiving modulated carrier wave energy comprising means for detecting received energy to provide modulation signals, means for developing a control voltage in the absence of received carrier energy, means for utilizing the control voltage to render inefficient an amplifier supplying electrical energy for detection, means for deriving a second control voltage from detected wave energy, means for regulating said amplifier gain, for controlling the level of wave energy subjected to detection, with said second control voltage, means for deriving a third control voltage from received energy whose amplitude exceeds a predetermined level, and means utilizing the third control voltage to render said detection inefficient.

4. A system of receiving signaling energy which includes means amplifying such energy, means demodulating the energy, means rectifying the amplified energy when the amplitude thereof exceeds a predetermined level thereby to provide a control voltage for preventing the reproduction of undesired noise impulses, means rendering said demodulation inefficient in response to said control voltage, means amplifying the demodulated energy, means rectifying the amplified modulation, and means for controlling said first mentioned rectification action in response to the rectified modulation voltage.

5. A method of receiving amplitude modulated carrier wave energy which includes detecting received carrier energy to provide modulation signals, developing a control voltage in the absence of received carrier energy, amplifying the carrier energy prior to detection, utilizing the control voltage to render inefficient said amplification, deriving a second control voltage from detected wave energy, controlling the said amplification with said second control voltage, rectifying received energy whose amplitude exceeds a predetermined peak level, and utilizing the last rectified voltage to render said detection ineffective.

6. A method of receiving signaling energy which includes amplifying such energy, demodulating the energy, rectifying the amplified energy when the amplitude thereof exceeds a predetermined level thereby to provide a control voltage for preventing the reproduction of undesired noise impulses, rendering said demodulation inefficient in response to said control voltage, rectifying the demodulated energy, and controlling said first mentioned rectification action in response to the rectified modulation voltage.

7. A method of receiving modulated carrier wave energy which includes detecting received energy to provide modulation signals, developing a control voltage in the absence of received carrier energy, utilizing the control voltage to render inefficient the supply of electrical energy for detection, deriving a sound control voltage from detected wave energy, controlling the level of wave energy subjected to detection with said second control voltage, deriving a third control voltage from received energy whose amplitude exceeds a predetermined level, utilizing the third control voltage to render said detection inefficient, rectifying the detected carrier energy to provide a fourth control voltage, and regulating said third voltage derivation with said fourth control voltage.

R. LEE HOLLINGSWORTH.
